UNITED STATES PATENT OFFICE

121,616

DESIGN FOR AN ILLUMINABLE JACK

Edward M. Pfauser, Elm Grove, Wis., assignor to
Blackhawk Mfg. Co., Milwaukee, Wis., a cor-
poration of Wisconsin

Application January 4, 1940, Serial No. 89,279

Term of patent 3½ years

To all whom it may concern:

Be it known that I, Edward M. Pfauser, a citizen of the United States, residing at Elm Grove, in the county of Waukesha and State of Wisconsin, have invented a new, original, and ornamental Design for an Illuminable Jack, of which the following is a description, reference being had to the accompanying drawing, forming part thereof.

In the drawing:

Fig. 1 is a perspective view of the illuminable

jack of the present new design showing the lifting arm in elevated position; and

Fig. 2 is a top plan view on a somewhat enlarged scale, of the illuminable lamp portion shown in Fig. 1.

The dominant or characteristic features of the new design are shown in solid lines.

I claim:

The ornamental design for an illuminable jack, substantially as shown and described.

EDWARD M. PFAUSER.
